UNITED STATES PATENT OFFICE.

HERBERT E. ERWIN AND FRANKLIN A. BOWERS, OF NEW BRITAIN, CONNECTICUT,
ASSIGNORS TO THE NEW BRITAIN MACHINE COMPANY, OF NEW BRITAIN, CONNECTICUT, A CORPORATION OF CONNECTICUT.

VENDING-MACHINE.

1,202,170.

Specification of Letters Patent. Patented Oct. 24, 1916.

Application filed July 14, 1914. Serial No. 850,924.

To all whom it may concern:

Be it known that we, HERBERT E. ERWIN and FRANKLIN A. BOWERS, citizens of the United States, residing at New Britain, in the county of Hartford and State of Connecticut, have invented certain new and useful Improvements in Vending-Machines, of which the following is a specification.

This invention relates to vending-machines, the object of the invention being to provide an apparatus of this character having simple and effective means by which the articles can be accurately discharged one at a time or in other desired order.

In the drawings accompanying and forming part of the present specification we have shown in detail one of the several convenient forms of embodiment of the invention, which to enable those skilled in the art to practise the same will be set forth fully in the following description. We do not restrict ourselves to this disclosure; we may depart therefrom in several respects within the scope of the invention defined by the claims following said description.

Referring to said drawings: Figure 1 is a front elevation with the front of the casing removed. Fig. 2 is an approximately vertical, central section of the machine, looking toward the right in Fig. 1. Fig. 3 is a practically similar view, but looking toward the left in Fig. 1. Fig. 4 is a view corresponding substantially to Fig. 3 and showing the parts in a different position. Fig. 5 is a detail view of the receiving-chamber, the runway leading thereto, the hold-back device and the jogger or agitator. Fig. 6 is a detail view of check-controlled mechanism.

Like characters refer to like parts throughout the several figures.

The machine can be used for vending or delivering articles of various kinds, one illustration of which is pencils, the discharge of which can be accomplished with or without the use of a coin or analogous device; in the organization shown there is check-controlled mechanism adapted to be operated by a coin of proper denomination, for instance a nickel, to effect the dispensing of an article when desired.

The different parts of the machine may be inclosed in any desirable casing, that shown for this purpose being denoted in a general

way by 2 and being in the form of a box 55 of sheet metal having a drop-down hinged door 3 at its front, usually held closed under lock and key, and by opening which access may be had to the interior of the casing for the purpose of loading the machine and 60 when coins are used in connection therewith, for collecting said coins.

Within the casing 2 and extending from one side to near the other side thereof, is a chute or runway as 4, shown as inclined, 65 and which constitutes a main or stationary support for the articles to be vended. The said chute or runway at its upper end has an upstanding flange 5 fastened as by one or more bolts to the adjacent wall of the 70 casing 2 interiorly thereof, and at its lower end has a depending portion 6 inwardly-flanged at 7 at its lower end, said flange 7 being connected by one or more bolts or otherwise to the bottom of the casing 2 75 interiorly thereof. The upright portion or wall 6 is spaced or separated from the adjacent wall of the casing 2 and the upper portion of this space presents a chamber 8' for receiving the articles as they gravitate from 80 the inclined chute or runway 4. The bottom of said chamber consists in the present case of an article supporting and dispensing member as 8 which is horizontally reciprocative and which has an abutment such as 85 the upstanding flange 9 at its rear end. In Fig. 3 the article supporting and delivering member 8 is shown as being in its retracted position and as supporting a pencil, one end of which is against the abutment 90 or flange 9, the pencil at such time being wholly within the casing or boxing 2. On the advance of said member 8 the pencil will be carried therewith and at a predetermined point, the forward end of said pencil will 95 be projected through a hole 10 in the door 3, the diameter of the hole being a trifle larger than that of the pencil, so that the projecting end of the pencil can be grasped and the pencil withdrawn. When said pencil is slid from off said part 8, a second pencil will gravitate thereonto.

We provide means for preventing the pencils choking at the entering end of the chamber or compartment 8', and for this purpose have shown the holdback or checking device 11 which as shown consists of a substantially U-shaped and somewhat resili-

ent plate attached at one terminal as by one or more bolts, to the interior of the casing 2 above the chamber or compartment 8', the opposite or free end of the said holdback or 5 checking device 11 being practically opposite the junction of the chute 4 and wall 6 and being separated therefrom a distance equal practically to the diameter of a pencil so as to insure that the pencils will not 10 crowd into the chamber or trough 8' but rather that they will pass positively thereto into one at a time. To facilitate free movement of the pencils the free portion of the holdback or checking member 11 diverges 15 at its free end away from the chute 4 to provide a throat of progressively increasing size from its delivery to its entering end.

The pencils are laid in a group on the chute or runway 4 and to insure their free 20 feed, we prefer for instance on each operation of the machine to agitate or jog them. We find that from various causes, the tendency of pencils and other articles is to stick but by agitating them slightly, their separation 25 will be positively assured. Means of different kinds may be provided for thus jogging or agitating the pencils or other articles, although that shown and now to be described has been found satisfactory.

30 The chute or runway 4 is shown provided upon its bottom near the high side thereof with the depending brackets or hangers 12 to which are pivoted the arms 13 connected by the web 14, these arms 13 constituting 35 suitable jogging or agitating means for the pencils and the chute or runway 4 having transverse slots 15 for the passage of said jogging or agitating arms 13, which it will be understood are practically of flat or plate 40 form. The two arms are normally located below the chute or runway 4 but on the operation of the machine as will hereinafter appear, said arms 13 are moved upward through the slots 15 and against the pencils, 45 loosening them up and if they be attached, separating them, thus insuring their free rolling or movement along the runway or chute 4.

50 The side walls of the casing 2 and the plate or wall 6 support a manually-operable shaft as 16, this shaft being preferably locked against movement normally by suitable check-controlled means and in the present case having means for operating the auxiliary support or article supporting and vending member 8 and for also operating the two jogging arms 13. Other means of a radically different character could be utilized instead of the described instruments. 55 60 65

Loosely supported by said transverse rock shaft, is the hub 17 of the crank arm 18, said hub having projections 19 between which is disposed the pin 20 rigid with the shaft, the two projections 19 being placed

with respect to the pin 20 as to permit on the initial movement of the shaft when in either of its two extreme positions, a certain amount of lost or relative motion for a reason that will hereinafter appear. Connected with the crank-arm 18 is the spring 18' the purpose of which is to automatically and yieldingly take up this lost motion. It will be assumed that said shaft 16 has been released through the agency of a coin and that it is rocked forward by the handle 22 connected to one of the projecting ends thereof. When said shaft has advanced a certain distance the pin 20 will be carried against the projection 19 on the left in Fig. 4 and will swing the crank arm 18 forward, thereby carrying the free end of said crank arm 18 against the web or connecting piece 14 of the agitating arms 13, lifting said web and hence the two arms. While return 85 movement of said agitating-arms 13 might be obtained by gravity, we prefer to use for this purpose the spring 23 connected with the web 14, for such purpose. The article supporting and vending or ejecting member 8 also receives its motion from the crank arm 18. To said crank arm is pivoted the forward end of the link 24, the rear end of which is pivoted to the lever 25 between the ends thereof, said lever being fulcrumed at its lower end within the casing 2 and its upper end being operatively connected as by the pivot 26 with the article supporting and vending member 8. The pivot 26 projects through an arcuate slot 27 in the wall or flange 6, the arc of said slot being struck from the center of movement of said lever 25. The depending flange 8" of the part 8 has a longitudinally-extending guide slot 28 to receive the guide-pin 29 on said wall or partition 6, said flange 8" fitting flatwise and sliding against said wall. Across the forward open end of the chamber or compartment 8' and situated therefore at approximately right angles to the line of movement of the articles as they are vended, is the barrier 30 which can be rigidly fastened to the plate 6 and which positively prevents two pencils being simultaneously carried forward. Below this barrier 30 and 105 extending diagonally or obliquely, is the guard 31 partly in the path of the articles, and which prevents an instrument being passed through the opening 10 to pull out an article, without the intervention of a 110 coin. This guard 31 is resilient or yieldable and is pushed to one side by a pencil as the latter is advanced in the manner already 115 described.

Rigid with the shaft 16 inside the casing 125 2 is the plate or disk 32 having a peripheral notch 33 to receive the tooth 34 of the pawl 35 pivoted between its ends within and to said casing, the tooth being normally held in the notch by the spring 36 connected to said 130

pawl. Also rigidly maintained in the casing is the coin-chute 37, the entering end of which is opposite the coin slot 38 in the door 3, the discharge end of said chute being 5 opposite the coin seat 39 on the arm 40 constituting a suitable coin support, and rigid with said shaft 16. A coin on being introduced into the chute 37 through the slot 38, passes along said chute and is discharged 10 from thence onto the seat 39 with its periphery in adjacence to the laterally-extending stud 41 on the pawl 35. Also rigid with the shaft 16 is the sector plate 41 to which one end of the pull spring 42 is connected, 15 the purpose of said spring being to return the parts connected with said shaft 16 to their initial positions. This spring also normally maintains the forward wall of the notch 33 against the tooth 34, said notch 20 being of greater extent than the tooth, so as to permit a certain amount of relative or free movement between the coin support or carrier 40 and the pawl 35.

It will be assumed that a coin is upon the 25 seat 39, it being understood that the arm 40 is between the sector plate 41 and the disk 32. Therefore, as the arm 22 is swung forward or toward the right in Fig. 2 the shaft 16 will be advanced as will the parts 32, 40 30 and 41, carrying the coin on the seat 39 against the stud or pin 50 and lifting the inner branch of the pawl 35 and hence the tooth 34 out of the notch 33, so that a complete forward movement of the shaft 16 can 35 be accomplished and thereby through the described parts effect the advance of the element 8 sufficiently to project a pencil through the hole 10 in the door 3. After the operative end of the pawl 35 has been 40 lifted, the coin drops from place into the tray 43 in the casing 3 on the floor or bottom thereof. As the arm 22 is moved forward the spring 42 is stretched, so that the parts 45 41, 40 and 32 as well as the handle 22 will be returned to their original positions by the power of said spring 42 when the arm 22 is freed, and just before the original positions are reached, the tooth 34 is projected into the notch 33 by means of the spring 36. 50 It will be clear that on the rocking of the shaft 16 the part 8 is first advanced and

then retracted. The sector plate 41 has several peripheral teeth 44 coöperative with the detent 45 actuated by the spring 46, the detent 45 through its coaction with said teeth 55 44 preventing backward movement of the sector plate 41 and therefore of the parts movable therewith.

What we claim is:

1. A machine of the class described comprising a casing, a chute in said casing, a wall extending downward from the delivery end of said chute and spaced from the adjacent wall of the casing, an article supporting and delivering member mounted for back and forth movement in the space between said walls, a lever mounted on the inside of the first mentioned wall and operatively connected with said article supporting and delivering member, the first mentioned 65 wall being slotted to provide for the passage of the connection between said lever and said member, and means for operating said lever to effect the advance of said member and thereby of an article supported thereby, 70 the casing having an opening for the passage of the article thus advanced.

2. A machine of the class described comprising a casing, a chute in said casing, an article supporting and delivering member 80 to receive the article from the chute, a manually operable rock shaft, a crank arm loose on said shaft and having projections, an arm rigid with said shaft and disposed between said projections, said last mentioned 85 arm by engaging one of the projections being adapted to advance the crank arm, means for retracting said crank arm, an operative connection between said crank arm and the article supporting and delivering 90 member, and an agitator for the articles on the chute located to be given an operative movement by said crank arm on the advance thereof.

In testimony whereof we affix our signatures in presence of two witnesses.

HERBERT E. ERWIN.
FRANKLIN A. BOWERS.
